SKIRT

Mae Louise Myers, also known as Mae Louise
Bruné, Washington, D. C.

Application May 8, 1950, Serial No. 160,778

7 Claims. (Cl. 2-211)

1

The present invention relates to ladies' skirts. It is well known that women's skirts, particularly those made of woolen fabrics and certain synthetic fabrics, become bulged or bagged at the seat portion (sometimes called "rump sprung" in the trade) due to frequent sitting of the wearer or sitting for long periods of time and that this bulging is objectionable and annoying to the wearer as it renders the garment unsightly in that the shape of the garment, as originally designed or fitted, becomes distorted; and this is so particularly with, so-called, straight skirts designed to produce a slenderizing appearance. Moreover, such "straight" skirts limit the stride of the wearer, when walking, and, when the wearer is in sitting position, they may rise or "ride" upwardly and do not properly cover the knees of the wearer and do not allow ease of movement of the legs or give a graceful effect.

The object of the present invention is to overcome the above drawbacks by constructing a skirt in a novel way to give a "straight" skirt effect but which may be manipulated to prevent such outward bulging or bagging at the seat portion thereof, as above mentioned, and will assure that the skirt will maintain a slenderizing design, when the wearer is in a standing posture, while affording an abundance of leg room, when the wearer is walking, and draping with fullness down over the knees, when the wearer is sitting.

It is also an object of the present invention that a skirt be constructed, as above generally defined, in a practical and acceptable manner which has a definite style or fashion appeal and, from the standpoint of workmanship, may be tailored and produced reasonably as compared with skirts of the conventional type.

These objects are attained broadly by designing a skirt garment that is divided at its rear portion and provided with an underskirt, petticoat or curtain, as part of the garment, within and behind the divided area and arranged so as to allow the fabric thereof—at one or both sides of said division—to be removed from the seat area when the wearer is seated yet, at the same time, will fully cover and clothe the wearer while in sitting or standing position. A garment having such features of this invention, as just stated, is particularly desirable for women who travel long distances upon trains or airplanes or are required to sit for long periods of time in an office or the like.

More specifically, the invention contemplates a unitary garment having an outer skirt and an inner skirt attached together at their waist-

2

band area, the outer skirt being slit or divided longitudinally of its length at the rear thereof with the divided portions overlapping one another throughout their length and circumferentially of the garment for a considerable distance—that is, to say, for a distance substantially equal to the seat area—with the outer or overlapping portion forming a flap unsecured at the waist-band but being detachably secured along the upper portion of its longitudinal marginal edge to the opposite portion of the underlapped portion of the outer skirt, when the garment is in normal and proper wearing position on its wearer. This construction allows the garment to be given the style-design desired, with the overlapping flap covering the seat of the wearer. The inner skirt is formed to have greater fullness than the outer skirt, such as by the provision of pleats, so that, when the wearer is about to assume a sitting position, the overlapping flap may be unfastened and drawn away from the rear portion of the garment toward a side of the wearer, thus exposing the underlapped portion of the outer skirt and such portion of the inner skirt as may appear, the fullness of the inner skirt giving an abundance of loose fullness to the garment—yet fully clothing the wearer—so that the fabric of the outer skirt will not rise or ride upwardly when the wearer is in sitting position but allows the skirt to fall over and cover the knees of the wearer and to gracefully drape from the thighs of the wearer, when in sitting position, whereby eliminating the strain and tension from the fabric of the outer skirt that produces the bagging or bulging of the seat portion. When in standing position, the flap portion may be fastened in position to give the skirt its normal style effect.

The invention resides in all that is shown and described in the following specification and in the annexed drawings which form a part of this specification.

In the drawings which illustrate one preferred embodiment of the invention as at present devised:

Figure 1 is a perspective view illustrating a wearer of the skirt of the present invention seated on a chair or stool and the manner in which the skirt may be manipulated while its wearer is in a seated position;

Figure 2 is a perspective view of the skirt of the invention viewed from the rear left side;

Figure 3 is a rear elevation of the skirt, with the rear overlapping seat flap or portion unfastened and hanging;

55

Figure 4 is an enlarged rear elevation of the skirt with one of its divided portions or flaps opened and with parts broken away to illustrate the details of construction;

Figure 5 is a fragmentary elevation of the rear portion of the curtain or inner skirt illustrating the manner of its construction as it appears from the inside of the skirt; and

Figure 6 is a transverse sectional view taken substantially on line 6-6 of Figure 4 to illustrate details of construction.

Like characters of reference mentioned in this specification will indicate similar and like parts throughout the several views of the drawings.

It is to be understood that the objects of the present invention, as above defined, may be carried out in a garment which may be modified in some details from that shown in the drawings, which latter is by way of illustration of one specific construction of a skirt embodying the invention. These variations or modifications will be obvious and some of such variations will be pointed out herein.

The garment of this invention is shown herein as comprising an outer skirt 10 whose rear portion is divided throughout its length and an inner skirt 11 secured to a common waistband 12, thus forming a garment unit. The inner skirt portion is preferably (though not necessarily) of thinner or lighter-weight material than the outer skirt 10 and is closed at its rear portion except for a placket 13 provided at said rear portion (preferably at a side-rear portion as shown) and extending downwardly from, and including, the waistband for a desirable distance to or about a point just above the seat portion of the garment, so as to allow the garment to be slipped on and off the wearer in a manner common to skirts as is well known.

The outer skirt 10 may be of one piece of fabric or may be made of a greater number of pieces or panels stitched or seamed together that will provide the length, breadth or pattern of the garment desired. The divided portion of the outer skirt is provided by the two lapped portions *a* and *b*lapping one over the other throughout the length of the skirt and circumferentially of the garment for a distance substantially that of the seat area. As shown, in Figs. 1, 4 and 6, underlapped portion *a* terminates at a line substantially coinciding with the adjacent edge of the placket 13 and is secured to the waist-band 12 together with the remainder of the skirt around to the other edge of the placket 13 except for the overlapped portion *b*. The flap or portion *b* forms a free flap, extending over and beyond the placket and having a conforming waist-band area *b*¹, and is detachably secured at or along the upper part of its longitudinal marginal edge *b*² to the opposite underlying portion *a* by buttons 14 and button holes 15 thus holding the flap *b* across the seat area of the skirt, covering the placket 13 and the division of the skirt and fully covering and obscuring the inner skirt 11. The skirt, as just described, assumes its normal style effect on its wearer, when in standing position.

Of course, it is to be understood that other closing means may be substituted for the button-hole 15 and the button 14, and, if desired, they may extend downwardly of the length of the skirt for such distance as may be preferred for assuring the maintenance of the overlapping portion *b* in its overlapping position and at the same time giving comfort in the wearing of the skirt.

The rear portion of the inner skirt 11 is formed

with a vertically disposed inverted or inwardly facing box-pleat 16, of generous proportions as illustrated, extending from just above the seat portion of the skirt—preferably from the lower end of the placket 13—to the bottom edge of the skirt. This box-pleat 16 is held in its formation by the horizontal stitching 16a at its upper end, as shown, but is not otherwise stitched—that is to say, that its folds are open longitudinally and open at their lower ends so as to give required fullness when the wearer is in a seated position, as shown in Figure 1.

As shown particularly in Figures 1 and 4, it is preferred in some cases that the longitudinal edge *a*¹ of the rear-portion *a* of the outer skirt extends to the adjacent edge 13a of the placket 13 and to the inner edge 16b of the adjacent fold of the box-pleat 16 and be secured thereto by a line of stitching 17. The placket may be held closed by any suitable means, such as the zipper 18 illustrated. The placket portion of the waist-band 12 may be additionally secured together at the waist-band portion by separable hooks-and-eyes 19.

When the wearer is about to assume a sitting position, the fasteners 14 and 15 are unfastened allowing the seat flap portion *b* to hang, as shown in Fig. 3, or it may be folded back to one side where the button hole 15 may engage over a button 20 as shown in Fig. 1. As this flap *b*, is not attached to the inner skirt 11 or to the waist-band, said portion *b* of the outer skirt may be drawn or brought to the side of the wearer so as not to be sat upon and, as the wearer assumes a sitting position, she will sit on the rear portion *a* and such portion of the inner skirt 11 as may be exposed, as shown in Fig. 1, the pleat 16 supplying the fullness of cloth necessary as to allow the fabric of the outer skirt 10 to accommodate itself to the sitting position of the wearer and fall in a graceful drape from the thighs and down-over the knees of the wearer.

Due to the fullness provided by the pleat 16, that part of the rear portion *a* of the outer skirt 10 below the placket also may be drawn to the side of the wearer and the wearer may sit entirely on the inner skirt 11, which fully covers and clothes the wearer at all times. Consequently, to this end in some forms of the garment of this invention, the stitching 17 may be eliminated, at least from the placket 13 downwardly, without impairing the advantages of the garment, particularly when the fabric of the outer skirt is of heavy material such as heavy weight woolens.

It is obvious that the skirt will not develop a "seat bulge" when the divided lapping portions *a* and *b* of the outer skirt 10 are manipulated as described; and, even if only the flap *b* is moved to one side, as shown in Fig. 1, so as not to be sat upon while the wearer is sitting, this bulging will not develop in the seat area of the underlapped portion *a* due to the fullness provided in the false or inner skirt or curtain 11 as strain is relieved therefrom. Furthermore, since the flap *b* forms the outer overlap at the seat of the garment and it is always to be moved to one side when the wearer is seated, it will present a smooth rear panel when the garment is normally adjusted for wear while the wearer is in standing position.

The construction of the skirt of this invention does not require that the seat flap *b* be fastened each time the wearer arises from sitting position, as in the case of frequent rising and sitting, because the flap *b* will hang gracefully from the waist-band at the placket 13, as shown in Fig. 3,

proper coverage of the wearer being assured by the inner skirt or curtain 11 and the hanging of the flap.

Manifestly, a skirt constructed according to the present invention allows the outer skirt to be designed to have a very snug streamlined appearance while at the same time, the wide inverted pleat 16 in the inner curtain or skirt in addition to the division of the outer skirt, will afford plenty of fullness to enable the wearer to walk comfortably with full strides and to assume a sitting position with grace without developing a baggy seat in the garment.

It is within the purview of the present invention that the inner skirt 11 may be modified to the extent that it may not extend entirely around the entire circumference of the garment but may only extend from its rear portion to a point adjacent the sides of the wearer, thus forming a curtain. However, such curtain should be attached to the outer skirt, preferably, only at the waist-band, as above described. Also, the box-pleat 16 may not be located in the inner skirt or curtain as illustrated, but may be deposited in the rear center of the skirt or at any other desirable place in the rear portion, or even in its front portion, so long as the required fullness provided thereby will be available when the wearer is in a sitting position and when the lapping flap portions *a* and *b* are separated from their normal position as shown in Figures 2 and 6. It is also within the purview of the invention that the box-pleat in the inner skirt or curtain 11 may be extended to the waist-band 12, although in practice it has been found that this is not necessary.

It is also within the contemplation of the use of this invention that the flap or overlap portion *b* need not, in all instances, be unfastened at 14-15, when the wearer assumes a sitting position, particularly when two or more of such fasteners hold said flap *b* in its overlapping position and extend for a short distance downwardly from the waist-band 12 but which will still allow the flaps *a* and *b* to be separated at the seat portion downwardly and drawn to the sides of the wearer, or which will permit the same manipulation with only the flaps *b*, as may be desirable on some occasions.

Of course, it will be further understood that the inner and outer skirts may be of the same length or one may be shorter than the other depending upon the effect to be produced, according to the style of the garment, and that this skirt may form part of a dress.

The skirt made in accordance with the present invention has many advantages from a practical standpoint, as set forth above, and also has style characteristics, all of which have been favorably received by the purchasing public.

Having fully described the above invention and at least one means by which the same may be carried out, as well as several variations that may be employed, it is to be understood that other variations and modifications may be made from the specific structure shown and described and that fall within the scope of the appended claims.

What I claim as new is:

1. In a woman's unitary garment, an outer skirt for encircling the wearer having a waist-band and being divided lengthwise throughout its length at its back portion, said divided back portions of said skirt lapping for a distance circumferentially of the skirt, an inner skirt of relatively lighter weight material than the outer

skirt attached to said outer skirt at said waist-band portion and disposed within the outer skirt to encircle the wearer and curtaining the opening in the outer skirt when said divided portions of the outer skirt are separated, separable fastening means detachably holding the lapping portions of the outer skirt in overlapped position, when fastened, and, when unfastened, permitting the lapping portions to be drawn from the rear of the wearer to one side of the wearer while in sitting position and means at said waist-band portion permitting the garment to be donned and doffed.

2. In a woman's garment, a skirt for encircling the wearer having a waist-band and being divided lengthwise throughout its length at the rear portion thereof, said divided back portions of said skirt providing lapping portions, a skirt-like curtain attached to the waist area of the skirt and disposed within the skirt at the rear portion thereof to hang and extend downwardly behind the divided portion and laterally from at least one side to the other side of the skirt, separable fastening means detachably holding the lapping portions of the skirt in overlapped position, when fastened, and a placket in said curtain at the divided area of the skirt permitting the skirt to be donned and doffed.

3. In a woman's unitary garment, a skirt having a separable waist-band and being divided at its back portion throughout its length and forming overlapped portions in the area of the seat portion of the skirt, the overlapping outer portion being unattached to the waist-band of the skirt for providing a back panel flap, separable fasteners for detachably maintaining the outer overlapping portion of the outer skirt in overlapped position, a skirt-like curtain attached to said waist-band on opposite sides of the separable portions of said waist-band and disposed adjacent to and behind said overlapped portions for substantially their length and at least from one side to the other side of the garment, an open pleat in said curtain extending longitudinally thereof, and a placket in said curtain extending from the separable portions of said waist-band for a distance downwardly.

4. In a woman's unitary garment, a skirt being divided in its back portion throughout its length, the divided portions forming overlapped portions in the area of the seat portion of the skirt, the overlapping outer portion being unattached to the waist-band area of the skirt for providing a back panel flap, separable fasteners for detachably maintaining the outer overlapping portion of the outer skirt in overlapped position, a curtain attached to said waist-band of the skirt and disposed adjacent to and behind said overlapped portions for substantially their length and at least from one side to the other side of the garment, a placket in said curtain disposed opposite the divided area of the outer skirt, and an open pleat in said curtain extending longitudinally from the lower end of said placket to the lower end of said curtain, the longitudinal edge of the underlying lapping portion being attached to the adjacent edge of said placket and to an adjacent fold of said pleat.

5. In a woman's garment, an outer skirt and an inner skirt connected together at their waist-band portion and substantially coinciding, said outer skirt being divided in its back portion throughout its length and forming lapping portions, the overlapping outer portion being unattached to the waist-band area, separable fas-

tener means at the upper longitudinal marginal edge of the outer overlapping portion of the outer skirt and at the contiguous underlying portion of inner lapping portions for detachably holding said lapping portions in overlapped position, and a placket in the inner skirt and waist-band portion thereof disposed opposite the divided area of the outer skirt.

6. A woman's garment comprising an outer skirt and an inner skirt connected together at their waist-band portion and substantially coinciding, said outer skirt being divided in its back portion throughout its length and providing lapped portions throughout the length of the skirt and for a substantial width of the seat portion of the skirt, the overlapping outer portion being unsecured to the waist-band area of the skirt, a placket in the inner skirt extending for a distance downwardly from and through the waist-band portion and disposed at the longitudinal edge of the underlapped portion, an open pleat in the inner skirt extending from the lower end of the placket to the lower edge of the inner skirt, and separable fastener means for detachably holding the overlap portion in overlapped position with respect to the underlap portion of the outer skirt from its waist-band downwardly for a distance.

7. A woman's garment comprising an outer skirt and an inner skirt connected together at their waist-band portion and substantially coinciding, said outer skirt being divided in its back portion throughout its length and providing

5 lapped portions throughout the length of the skirt and for a substantial width of the seat portion of the skirt, the overlapped outer portion being unsecured to the waist-band area of the skirt, a placket in the inner skirt disposed at the longitudinal edge of the underlapped portion, an open pleat in the inner skirt extending from the inner end of the placket to the lower edge of the inner skirt, the longitudinal edge of the underlapped portion of the outer skirt being attached to the adjacent edge of said placket and to an adjacent fold of the pleat, and separable fastener means for detachably holding the overlap portion in overlapped position with respect to the underlap portion of its outer skirt from the waist-band downwardly for a distance.
